UNITED STATES PATENT OFFICE.

JOHN L. KIVLAN, OF BOSTON, MASSACHUSETTS, ASSIGNOR, BY MESNE ASSIGNMENTS,
TO WILLIAM L. WALKER, OF WORCESTER, MASSACHUSETTS.

JAR-TRIMMING MACHINE.

Application filed March 4, 1924. Serial No. 696,774.

This invention relates to machines for applying to glass fruit jars and the like the "trimmings" or metallic portions by means of which the top is secured in place on the jar. The invention relates especially, although not exclusively, to jar trimming machines of the type shown and described in my prior Letters Patent No. 1,456,276, May 22, 1923, and has for its general objects to improve and simplify machines of this character and to insure their accurate and reliable operation, whereby the possibility of defective work is reduced to a minimum and the capacity of the machine increased.

The more particular objects of the invention, together with means whereby the same may be carried into effect, will best be understood from the following description of a preferred embodiment thereof illustrated in the accompanying drawings. It will be understood, however, that the particular construction described and shown has been chosen for illustrative purposes merely, and that the invention, as defined by the claims hereunto appended, may be otherwise practised without departure from the spirit and scope thereof.

In said drawings:

Fig. 1 is a side elevation, partly in section, of the complete machine.

Fig. 2 is a section, taken substantially on the line 2—2, Fig. 1, of the means for operating the twister.

Fig. 3 is an enlarged side elevation of the twister.

Fig. 4 is a longitudinal section of the twister, taken substantially on the line 4—4, Fig. 3.

Fig. 5 is a detail section, taken substantially on the line 5—5, Fig. 1, of the cam bar for controlling the bender and wipers.

Fig. 6 is a plan view of the complete machine.

Fig. 7 is a detail transverse vertical sectional view, taken substantially on the lines 7—7, Figs. 1 and 6, illustrating the means for positioning the ends of the wire of the trimming.

Fig. 8 is a view showing the trimming in condition to be applied to the neck of the jar.

Fig. 9 shows a jar to which the trimming has been applied.

Figs. 10 to 14, inclusive, are diagrammatic

views illustrating the operation of the bender, wipers, twisters and flattening members.

Figs. 15 and 16 are detail views illustrating the positioning of the ends of the wires.

Referring to Figs. 8 and 9, at A is shown the jar to which the trimming is to be applied, the neck being shown at a and the cover at B. The trimming herein shown consists of a tie wire C and two hook-shaped clamps D, D, secured to the tie wire by toggle plates E, E. The trimming is applied to the neck of the jar by bending the tie wire C about said neck, twisting the ends of said tie wire together, as shown at e, and thereafter flattening said ends against the jar neck.

The frame of the machine is not shown in detail and may be of any suitable design to provide a table 20 and a base 21. Each jar A to be trimmed is placed on the table 20 between an upright plate 22 and a suitable positioning gauge or cleat 23, which plate and cleat center said jar and hold the same against displacement by the working instrumentalities.

The mechanism for bending the tie wire C about the neck of the jar comprises a bender 30 and a pair of wipers 31 which, as herein shown, are carried at the upper ends of elongated levers 32 and 33 pivoted at their lower ends to brackets 34 and 35 carried by the base 21 and extending through slots 36 and 37 to the table 20. The lever 32, which carries the bender 30, as operated by means of a spring 38 secured at one end to said lever and at the other to the table 20, while the levers 33, which carry the wipers 31, are operated by springs 39 each secured at one end to its respective lever 33 and at its opposite end to said table, the spring 38 tending normally to draw the bender 30 toward the jar, and the springs 39 tending normally to draw the wipers 31 toward one another.

The movements of the levers 32 and 33, under the influence of the springs 38 and 39, are controlled by a cam bar 40 having a wedge portion 41 interposed between the levers 33 and an end portion 42 constituting a pusher which engages the lever 32. The cam bar 40 may be moved longitudinally by any suitable mechanism, said mechanism, as herein shown, comprising a piston 43 secured to said cam bar and operating in a fluid pressure cylinder 44 supported by a bracket 45 beneath the table 20 and adapted to receive

pressure fluid through pipes 46 under the control of any suitable valve mechanism, not shown.

The bender 30 comprises a pair of arms disposed respectively at opposite sides of the centre of the jar A and formed substantially to fit the neck a when moved into engagement therewith. The wipers 31, which are located at the opposite side of the jar from the bender 30, are similarly formed to conform with the shape of said neck at their points of engagement therewith. The bender 30 and wipers 31 are each formed at their ends with notches to engage the wire C.

In operation, the operator places the tie wire of a trimming in the notches in the ends of the arms of the bender 30, as shown in Fig. 6, and holds the same in said notches until fluid pressure is admitted to the cylinder 44 in such a manner as to move the cam bar 40 rearwardly, or toward the right in Fig. 1. The first step of such movement is to permit the lever 32 to move under the influence of the spring 38, the levers 33 being still held apart by flat portions 47 on the wedge 41. Movement of the lever 32 causes the tie wire C to be partially bent about the neck of the jar, as shown in Fig. 10. Thereafter, continued movement of the cam bar 40 permits the springs 39 to draw the levers 33 and wipers 31 toward one another, said wipers, by engagement with the wire C, completing the bending so as to cause the ends of said wire to be crossed, as shown in Fig. 11, ready for the action of the twister hereinafter described. Movement of the cam bar 40 in the opposite direction serves to separate the wipers and retract the bender 30, thereby restoring the parts to their original position.

Mounted on a bracket 50 on the upper side of the table 20 is a frame 51 in which is mounted, for rotary and axial movement, a horizontal shaft 52 carrying at its end a twister for twisting together the crossed ends of the wire C. As shown most clearly in Figs. 3 and 4, the twister comprises a head 53 secured, as by a set screw 54, to the end of the shaft 52 and having fixed thereto a pair of spaced parallel flattening or depressing fingers or members 55 symmetrically disposed with respect to the axis of said shaft. Guided on the fingers 55 for movement in the direction of the axis of the twister is a slide 56 formed with a pair of spaced parallel lips 57 separated by a V-shaped nose 58 adapted to enter between the crossed ends of the tie wire, which ends are received between said lips. Interposed between the head 53 and slide 56 is a spring 59 tending normally to hold said parts separated while permitting the slide to yield in the direction of the axis of the twister. The outward movement of the slide 56 under the influence of the spring 59 is limited

by studs 60 on the fingers 55 which engage notches in plates 61 secured to the slide.

Secured to the shaft 52 within the frame 51 is a cylindrical cam member 62 having a helical groove 63. Guided on the frame 51, for reciprocatory motion in a direction parallel to the axis of the shaft 52 and twister, is a slide 64 having a central opening to receive the cam member 62. The slide 64 is reciprocated in the frame 51 by means of a bifurcated lever 65 comprising a pair of arms secured to a rock shaft 66 journalled in the bracket 45, the outer ends of said arms being slotted to receive studs 67 and 671 projecting from the slide 64. The stud 67 is extended into the opening in the slide to engage the groove 63 in the cam member 62, as shown in Fig. 2. The outer end of the cam member 62 is formed with a longitudinal bore to receive the end of a guide member 68 having a feather 69 which is received in an interior longitudinal groove in said cam member, thereby forming a splined connection between said parts adapted to hold the shaft 52 against rotation while permitting axial movement thereof. The lever formed by the arms 65 is oscillated about the axis of the rock shaft 66, to reciprocate the slide 64 in the frame 51, by means of a fluid pressure motor comprising a piston 70 having a piston rod 72 operatively connected with one of said arms, said piston working in a cylinder 71 to which fluid pressure may be admitted through pipes 73 under the control of a suitable valve mechanism, not shown.

In operation, after the tie wire C has been bent around the neck of the jar by the bender 30 and wipers 31, as above explained and as shown in Fig. 11, the arms 65 are rocked to move the slide 64 forward or toward the left in Fig. 1. During the first part of this movement the shaft 52 is held against rotation by its splined connection with the guide member 68 and is therefore moved axially or longitudinally out of engagement with said guide member, thereby causing the lips 57 of the twister to engage the crossed ends of the wire C, as shown in Fig. 12, and the nose 58 to enter between said ends and spread the same apart, if necessary. After the cam member 62 has been disengaged from the guide member 68, further axial movement of the shaft 52 and twister is prevented by the engagement of the latter with the jar, and continued movement of the slide 64 causes the stud 67 to co-operate with the groove 63 in said cam member to rotate the twister through about 180 degrees, thereby twisting the ends of the wire together, as shown in Fig. 13. When the stud 67 reaches the end of the cam groove 63, the slide 64 may be further moved to cause a further axial movement of the twister, the slide 56 yielding against the spring 59.

59 to permit such movement, the flattening fingers 55 being thereby brought into engagement with the twisted ends of the wire to flatten the same against the neck of the jar, as shown in Fig. 14. It will thus be seen that continued movement of the slide 64 in one direction causes the twister to be moved into engagement with the work and thereafter rotated, and may also be utilized to 10 cause the operation of the flattening fingers.

In order, however, to insure the effective flattening of the ends of the wire against the neck of the jar, means are preferably provided whereby the power for imparting 15 the final axial movement to the shaft 52 may be applied thereto with increased leverage. To this end, the guide member 68 is, as herein shown, in the form of a plunger guided for longitudinal movement in the frame 51 20 but held against turning therein by the feather 69. Interposed between the frame and a head 84 on said plunger is a spring 74 which holds said head in engagement with a lever 75 pivoted at 76 to a lug 77 on 25 the frame 51 and having its lower end slotted to receive a stud 78 projecting from the piston rod 72. The arrangement of the fulcrums of the levers 65 and 75, and the points of connection of said levers with the piston 30 rod 72 and with the slide 64 and plunger 68, respectively, are such that the movement of said plunger will be relatively small with respect to the movement of said slide, although the force applied thereto will be 35 correspondingly greater. The longitudinal movement of the shaft 52 by the slide 64 therefore causes the cam member 62 to disengage the plunger 68, as above explained, but after such longitudinal movement is ar- 40 rested, and the shaft rotated through 180 degrees, continued movement of the plunger by the lever 75 causes the spline 69 to re-engage the end of said cam member so as to cause the flattening fingers 55 to be forced 45 against the ends of the wire under the increased leverage afforded by said lever 75. In order to cause the final axial movement of the twister to be effected by the relatively slow movement of the plunger 68 by the 50 lever 75, rather than by the relatively quick movement of the slide 64 by the lever 65, a yielding connection is interposed between the latter lever and the piston rod 72. As shown in Fig. 1, the end of said piston rod 55 is guided in one end of a sleeve 79 carried by the bracket 45 and in the opposite end of which is received a rod 80 pivoted to the lever 65, a spring 81 of less strength than the spring 59 being interposed between the 60 ends of said rods, whereby the thrust of the piston rod will be communicated to the lever through said spring. Said lever 65 is returned to normal position, when the piston rod is retracted, by means of a spring 82

connected at one end to the lever 65 and at 65 its opposite end to the table 20.

Since the twister is, during its operative stroke, always rotated in the same direction, it is necessary that the ends of the wire C be properly superposed in order to cause the 70 same to be twisted together. Thus, by reference to Figs. 15 and 16, it will be seen that if the operative rotation of the twister be in a counter-clockwise direction, as indicated 75 by the arrow, the ends of the wire C must, in order to be twisted together, be superposed as shown in Fig. 16, since if in the position shown in Fig. 15 they would be separated and not twisted together by the rotation of the twister. In order to insure the 80 proper positioning of the ends of the wire for the action of the twister, means are provided for guiding said ends during the bending operation. As herein shown, said ends, 85 as they are bent around the neck of the jar by the bender 30, are caused to enter openings 83 (Figs. 7 and 10) in the plate 22, which is located between the work and the twister. Communicating with the openings 83 are slots 85 leading to a central opening 90 86 through which the twister operates, said slots being vertically offset with respect to one another and providing fixed offset guides 95 which are engaged by the ends of the wire, as the latter is bent by the wipers 31, to guide said ends into the predetermined superposed position required for the operation of the twister.

Having thus described my invention, I claim:

1. In a jar trimming machine, in combination, a bender for bending the wire of the trimming around the neck of a jar, a spring for forcing said bender against the wire, wipers to complete the bending, and a pusher for retracting said bender, said pusher including a cam bar having a wedge portion for retracting said wipers.

2. In a jar trimming machine, in combination, a pair of co-operating wipers for bending the ends of the wire of the trimming around the neck of the jar, spring means for forcing said wipers toward one another, and a wedge for separating said wipers.

3. In a jar trimming machine, in combination, a bender for bending the wire of the trimming around the neck of the jar, a spring for forcing said bender against the wire, a pair of cooperating wipers to complete the bending, spring means for forcing said wipers toward one another, and a longitudinally movable cam bar having a wedge portion for separating said wipers and an end portion constituting a pusher for re-tracting said bender.

4. In a jar trimming machine, the combination with mechanism to bend the wire

- of the trimming around the neck of the jar and cross the ends thereof, of fixed means for guiding said ends into a predetermined superposed position.
5. In a jar trimming machine, the combination with mechanism to bend the wire of the trimming around the neck of the jar and cross the ends thereof, of fixed means for guiding said ends into a predetermined superposed position, and means for twisting said superposed ends together.
6. In a jar trimming machine, in combination, a bender to bend the wire of the trimming around the neck of the jar, wipers 15 for crossing the ends of said wire, and fixed means for guiding said ends into a predetermined superposed position.
7. In a jar trimming machine, the combination with mechanism to bend the wire 20 of the trimming around the neck of the jar and cross the ends thereof, of a pair of fixed, offset guides engaged by said ends as said wire is bent for guiding said ends into a predetermined superposed position.
- 25 8. In a jar trimming machine, the combination with mechanism to bend the wire of the trimming around the neck of the jar and cross the ends thereof, of fixed means for guiding said ends into a predetermined superposed position, said means comprising a plate having openings to receive said ends as said wire is bent and relatively offset slots communicating with said openings respectively.
- 30 9. In a jar trimming machine, in combination, a rotatable and longitudinally movable shaft, a twister carried thereby, a cam member on said shaft having a helical cam groove, a slide guided for movement longitudinally of said shaft and having a 35 stud engaging said groove, a lever for reciprocating said slide, and a guiding member having a splined connection with said shaft for holding the latter against rotation until moved longitudinally out of engagement therewith.
- 40 10. In a jar trimming machine, in combination, a twister including a head for twisting together the ends of the wire of the trimming on the neck of the jar, a shaft for supporting said twister head, means carried by said twister for depressing said ends upon said neck, and operating means mounted on said twister head supporting shaft continuously movable in a 45 single direction for successively engaging
- said twister with said wire, rotating the same, and operating said depressing means.
11. In a jar trimming machine, the combination with a rotatable and axially movable twister for twisting together the ends of the wire of the trimming on the neck of the jar, said twister comprising a head provided with members for depressing said ends upon said neck and an axially yielding member provided with means for engaging said ends, a horizontal shaft for supporting the twister head, of means mounted upon said shaft and continuously movable in a single direction for successively engaging 60 said yielding member with said ends, rotating said twister to twist said ends, and further moving said head to cause said depressing members to flatten said ends, said yielding member yielding to permit said last 65 named operation.
12. In a jar trimming machine, in combination, a rotatable and axially movable shaft, a twister carried thereby for twisting together the ends of the wire of the trimming on the neck of the jar, means carried 70 by said twister for depressing said ends upon said neck, a plunger disposed coaxial with said shaft and having a splined connection therewith, means for moving said shaft axially out of engagement with said plunger to engage said twister with said ends and thereafter rotating the same to twist said ends, and means for finally reengaging said plunger with said shaft and 75 giving the latter a further axial movement to operate said depressing means.
13. In a jar trimming machine, in combination, a rotatable and axially movable shaft, a twister carried thereby for twisting together the ends of the wire of the trimming on the neck of the jar, means carried 80 by said twister for depressing said ends upon said neck, a plunger disposed coaxial with said shaft and having a splined connection therewith, a slide movable in a direction parallel to the axis of said shaft, co-operating cam means carried by said shaft and slide respectively for converting axial movement of said slide into rotary movement of said shaft, a lever for reciprocating said slide, a second lever for moving said plunger, and operating means for said levers including a common actuator and a yielding connection to said first named lever.
- In testimony whereof I affix my signature,
- JOHN L. KIVLAN.
